Specification for Design.

Patented Mar. 27, 1917.

Application filed January 20, 1917. Serial No. 143,530. Term of patent 7 years.

To all whom it may concern:

Be it known that we, ROBERT Y. BARROWS, a citizen of the United States of America, residing in the town of Rutherford, in the county of Bergen and State of New Jersey, and GEORGE V. STRAHAN, a citizen of the United States of America, residing in the city of Newark, in the county of Essex and State of New Jersey, have invented a new, original, and ornamental Design for a Hanger for Lighting-Fixtures, of which the

following description, in connection with the accompanying drawing, is a specification.

Figure 1 of the drawings is an elevation of a hanger for lighting fixtures showing our new design; and Fig. 2 is a plan view of the underside of the hanger.

We claim as our invention:

The ornamental design for a hanger for lighting fixtures, as shown.

ROBERT Y. BARROWS.
GEORGE V. STRAHAN.
